ROPE HOLDER

George H. Beers, Sr., Pittsburgh, Pa., assignor, by direct and mesne assignments, of one-half to George M. Crawford, Borough of Pitcairn, Pa., one-fourth to George W. Jones, III, one-eighth to Joseph T. Flynn, and one-eighth to Perry F. Flynn, all of Pittsburgh, Pa.

Application July 29, 1938, Serial No. 221,997

3 Claims. (Cl. 24—131)

This invention relates to a rope holder or anchoring device by means of which a rope may be dead-ended or secured to a post or other object to which it is to be fastened without requiring the tying of any knots.

The device of the present invention may be employed for the stringing of clothes lines and may also be designed for use in connection with ropes of various sizes for numerous purposes where a rope has to be suspended between two or more anchorages. According to the present invention, there is provided a supporting structure or anchoring device having a stem portion with an eye therethrough. The rope in being anchored is looped. The loop is passed through the eye and the loop is then turned back over the eye and pulled tight. The loop in contracting about the stem at the base of the eye draws tightly over the two stretches of rope from which the loop is formed, firmly holding them from slipping. The operation of fastening the rope to the anchoring device may thus be very easily and quickly effected without the tying of any knots, and the rope when so secured cannot slip. To release the rope it is only necessary to force the contracted loop back over the eye until the loop may be drawn back through the eye and the rope thus fully disengaged from the holder.

The invention may be readily understood by reference to the accompanying drawing which illustrates one form of my invention and in which,

Figure 1 is a perspective view showing the rope holder in use for attaching a rope such as a clothes line to a post;

Figure 2 is a plan view of the holder shown in Figure 1;

Figure 3 is a perspective view of a rope holder embodying my invention and showing the first step in fastening the rope to the holder. In this view the holder is of a slightly modified shape from that shown in Figures 1 and 2;

Figure 4 is a view similar to Figure 3 illustrating the final step in fastening the rope; and

Figure 5 is a perspective view similar to Figure 4 but showing the holder turned over.

In the drawing the holder shown in Figures 1 and 2 is essentially the same as shown in Figures 3, 4, and 5, except in Figures 1 and 2 one end of the frame is contracted to form an eye, whereas in Figures 3, 4, and 5, this one bend is eliminated. The construction is otherwise the same. Similar reference numerals have been used throughout to designate corresponding parts.

The device comprises a supporting frame 2 having an end portion 3 which may be slipped

over a hook or which may be otherwise secured to the post or other member to which the rope is to be anchored. The frame 2 is provided with a tongue or projection 4 having a stem portion 5 and an eye portion 6, the projections extending in a direction away from the pull of the rope. The device is preferably formed from a piece of heavy stiff wire such as galvanized steel wire. This wire is bent as shown in Figure 2 to provide a generally triangular frame having leg portions 2a diverging from the end 3 to the base of the frame. One leg 2a is bent transversely inward as indicated at 2b and then is further bent into loop form. The two parallel portions 5a and 5b of the looped wire form a part of the stem 5. The other leg at 2a is bent inwardly to provide the base portion 2c of the frame, and 5c the free end of the wire is bent inwardly between the portions 5a and 5b so that the stem 5 is comprised of three parallel reaches of wire. These parallel reaches of wire may be soldered or welded together as indicated by the shaded circles 7 in the drawing. As thus formed from a single piece of wire, the device can be economically constructed, and by reason of the three parallel reaches of wire in the stem 5, the stem 5 will be relatively stiff and resistant to bending.

In use the frame 2 may be secured to a hook, as for example, the hook A in Figure 1, which hook is secured to a post B to provide an anchorage for the rope holder. It will be understood that other forms of anchorage may be employed than the hook A. The rope to be stretched between the post and another point of suspension is formed into a loop C. This loop is pushed through the eye 6 as shown in Figure 3. The loop is then pushed forwardly so as to pass over the loop 4. Tension is then applied to the rope causing the rope loop C to contract about the stem portion 5 of the tongue. As shown in Figure 5, the looped rope C as thus contracted about the stem crosses over the two portions of the rope from which the loop in the rope is made, contracting upon these portions of the rope. When pulled tight, the rope cannot slip and will be firmly anchored. To release the rope, the loop C in Figure 5 is merely forced forward over the end of the eye until it is clear of the eye and then it will assume the position shown in Figure 3, and the loop in the rope can be pulled out through the eye. The rope can be anchored in this way adjacent the end of the rope or the anchorage can be put at any suitable point intermediate the ends of the rope. In other words, the invention does not require that the anchorage

be made at the end of the piece of rope. In stringing a clothes line, for instance, one end of the rope can be fastened as shown in Figure 1. At an intermediate point in its length the clothes line can be looped in the manner indicated and thus fastened.

A clothes line or any other rope to be fastened to a point of anchorage can through the use of this device be very quickly and conveniently anchored without the tying of any knots. After 10 a few trials, a person using the device can become very adept at fastening the rope and having it quite taut. When it is used as a clothes line holder, the device has a further advantage in 15 that if one stretch of the clothes line breaks, the slack created by the break cannot be transmitted past the holder into another expanse of the line. The device can be cheaply manufactured and sold, and it does not require the use 20 of any special hardware for mounting it on a post. When used in connection with the clothes line, it may be taken in along with the clothes line so as not to rust or become dirty.

It is to be understood that the invention may 25 be embodied in various forms other than the one shown. The particular shape illustrated is one which can be very conveniently bent from a single length of wire with a minimum amount of wire being required to form a sturdy device. 30 The particular shape, however, is not material other than it is desired that the projection 4 shall have a stem 5, the width of which is less than the maximum diameter of the eye so that 35 the loop as it is drawn tight will tend to go in the direction of the pull on the rope and contract about the rope. Instead of being formed from wire, the device may be formed from a malleable casting or forged, or may be stamped

from a sheet metal, and various changes and modifications may otherwise be made therein within the contemplation of the invention and under the scope of the following claims.

I claim:

1. A rope holder comprising a rigid supporting frame having means at one end for engaging an anchoring means to which the rope holder is to be fixed, the other end of the frame having a projection thereon extending toward said first 10 end in substantially the plane of the frame, said projection having a solid neck portion and having an enlarged eye portion thereon at the outer end of the neck and through which a loop of the rope to be held may be passed.

2. A rope holder comprising a rigid wire frame in the form of a closed loop having a narrow portion at one end adapted to engage an anchoring means to which the rope holder is to be fixed, there being an integrally formed projection at the other end of the loop extending toward 20 said narrow portion in the plane of the loop, said projection comprising portions of the wire shaped to provide a closed neck with an enlarged eye at the free end of the neck, said 25 eye being of a diameter such that a loop of the rope to be held may be passed therethrough.

3. A rope holder comprising a supporting frame in the form of a substantially triangular loop having a projection extending inwardly forming 30 a base of the triangle toward an apex thereof in substantially the plane of the loop, said projection having a solid stem portion with an enlarged terminal at the free end thereof, said 35 terminal having an opening therethrough providing an eye to receive a loop of the rope to be held.
